UNITED STATES PATENT OFFICE.

ADOLPH E. KLOTZ, OF NEW YORK, N. Y.

FIREPROOF PARTITION.

No. 823,052.

Specification of Letters Patent.

Patented June 12, 1906.

Application filed May 4, 1905. Serial No. 258,751.

To all whom it may concern:

Be it known that I, ADOLPH E. KLOTZ, a citizen of the United States, residing in New York, county of New York, and State of New York, have invented a new and useful Improvement in Fireproof Partitions, of which the following is a description.

This invention relates to the art of building construction, and has particular reference to partition-walls and other analogous structures to be used in buildings and architecture generally.

Among the objects of this invention the following may be noted: to provide a partition or wall structure which will be solid, compact, sanitary, and fireproof; to provide a partition or wall composed of simple, readily-assembled elements, producing a compact and solid foundation or filling for the walls of all kinds of architectural structures; to provide a composite filling to be used in the formation of walls and analogous structures in modern buildings, providing a supporting medium to be disposed between the studs or beams as a substitute for bricks, &c.; to produce a wall, partition, or other analogous composite structure for buildings of modern construction which will be light, strong, fireproof, and which can be built or 30 put together with great rapidity and ease and at a cost considerably less than that now possible in modern architectural fabrications.

With these objects in view and others incidental thereto, which will be detailed during the course of this description, my invention consists in the parts, features, and combinations of elements hereinafter described and claimed.

The accompanying drawings illustrate a construction disclosing an embodiment of my invention, wherein—

Figure 1 is an elevation of a section of a partition or wall involving the structural features of my invention. Fig. 2 is a section on the line 2 2 of Fig. 1, and Fig. 3 is a perspective view of a form of plaster block which may be used in the structure of my invention.

In the drawings the plaster block is indicated by the numeral 1, the same being rectangular in form and composed of any material suitable for the purpose. This plaster block is ordinarily bored longitudinally, as at 2, for the usual purposes and may be provided 55 in its longitudinal edges with a groove 3, or said edges may be flat or plain, as shown at 4.

These plaster blocks are employed as shown in Fig. 1 and are of a width to almost fill the space between the wall studs or beams 5, which latter may be of wood, metal, or any other material found suitable or usually employed for the purpose. The plaster blocks are secured in place by means of one or more nails 6, driven diagonally through the same at the top and into the stud 5, the heads of said nails being countersunk in the top of the block, as clearly shown in Figs. 1 and 2. By this means the blocks are firmly held from movement as a preliminary to building up the structure as a whole. After the blocks are set in place mortar, cement, or other similar substance will be run or forced into the space between the studs and the blocks, as shown at 7, and if the blocks are grooved, as shown in Fig. 3, a key 8 will be formed thereby, which will act as an additional means for holding the parts together when the cement becomes set, it being found, however, that the cement will firmly hold the blocks to the studs without the grooves and irrespective of the substance of either the blocks or studs. The cement filling being in place, the joints between the blocks and studs are covered by strips of woven-wire meshing 9, as clearly shown in Figs. 1 and 2, and this wire mesh may be placed on either one or both sides of the wall structure. The wire mesh may be of any breadth desired, but should fully cover the joint between the stud and the blocks, and said wire mesh is held in place by means of a suitable number of U-shaped staples 10, driven through the said mesh and into the blocks, as clearly shown. By this means the juncture between the blocks and studs of the wall structure is so 95 solidified, strengthened, and rendered impossible of fracture or displacement, and the structure as a whole is ready to receive the usual coating of mortar or other substance commonly employed for the purpose.

In order to illustrate the general principle of this invention, the drawings show the wall or partition structure to consist of merely one thickness of a plaster block; but it will be obvious that a plurality of blocks may be placed face to face, thus making the partition or wall of increased thickness, in which event the wire cloth or mesh 9 will be placed on the two surfaces of the structure and not on each surface of the blocks, as shown in the drawings.

From the above description it will be seen

that in the simplest form contemplated my invention involves a partition or wall composed of a plurality of blocks jointed to a stud or beam by means of what may be termed "temporary" fasteners—viz., the nails 6—and permanently held in place by means of keys of a cementitious substance—such, *e. g.*, as 7—and solidified and strengthened by the application of laths of wire mesh, such as 9. Obviously various modifications may be made in the construction of partition-walls of this nature within the scope of my invention, and the size and extent of said wall is without limit, inasmuch as the length and width of the same may be increased by the mere addition of blocks both vertically and laterally, as shown in Fig. 1.

Among the advantages of this invention the following may be noted: A composite partition or wall for architectural structures is produced which is light, strong, and fire-proof; the usual brick fillings employed in such structures are entirely done away with, and the structure produced is warm in winter and dead to sound; by the structure described the use of the several coatings of plaster, &c., is obviated, thus cheapening the construction of partitions and walls, inasmuch as it is only necessary to apply to the structure of this invention a single outside or "brown" coating; by closing up all cracks and crevices no chance is afforded for mice or vermin of any kind nesting or lodging therein; and the structure is of such character that shrinkage thereof is impossible, and the settling, warping, and cracking of walls is prevented.

Having thus described my invention, what

I claim, and desire to secure by Letters Patent, is—

1. The combination, in a partition or wall, of a series of vertical studs, plaster blocks set between said studs, cement keys inserted between the edges of the blocks and the studs and between the contiguous edges of adjacent blocks for permanently securing the blocks and studs together, and woven-wire laths permanently secured to the surface of the blocks on opposite sides of the studs and extending lengthwise of the latter, whereby a permanent and fireproof juncture between the said studs and blocks is produced and relative movement between the parts of the said joint is prevented.

2. The combination, in a partition or wall, of a series of vertical studs, plaster blocks set between said studs, the said blocks being secured to the studs by means of temporary fasteners to preliminarily hold them in place, cement keys applied between the blocks and studs and between the contiguous edges of adjacent blocks for permanently securing the studs and blocks together, and means applied to the surface of the blocks and studs at the points between the same to prevent relative displacement thereof and completely cover the said joint, thus producing a solid, fire and vermin proof connection.

In testimony whereof I have hereunto signed my name in the presence of two subscribing witnesses.

ADOLPH E. KLOTZ.
